UNITED STATES PATENT OFFICE.

OLIVER S. WEDDELL, OF MCKEESPORT, PENNSYLVANIA.

RAIL-JOINT.

SPECIFICATION forming part of Letters Patent No. 694,122, dated February 25, 1902.

Application filed April 26, 1901. Serial No. 57,548. (No model.)

To all whom it may concern:

Be it known that I, OLIVER S. WEDDELL, a citizen of the United States of America, residing at McKeesport, in the county of Allegheny and State of Pennsylvania, have invented certain new and useful Improvements in Rail-Joints, of which the following is a specification, reference being had therein to the accompanying drawings.

10 This invention relates to certain new and useful improvements in rail-joints, and has for its object the provision of novel means whereby the use of threaded bolts and nuts is entirely dispensed with.

15 The present invention further aims to construct a device of this character that will be extremely simple in construction, strong, durable, and comparatively inexpensive to manufacture.

20 The herein-described invention further contemplates to construct a fish-plate in such a manner that when the same is properly adjusted to the desired position a wedging action of the fish-plate will take place against 25 the web of the rail, this being brought about by the peculiar construction of the fish-plate adjacent to the openings formed therein, all of which will be hereinafter more fully described, and specifically pointed out in the 30 claim.

35 In describing the invention in detail reference is had to the accompanying drawings, forming a part of this specification, wherein like numerals of reference indicate corresponding parts throughout the several views, and in which—

40 Figure 1 is a side elevation of my improved rail-joint applied in position to the rails. Fig. 2 is a similar view of the opposite side of the 45 rails. Fig. 3 is an end view thereof. Fig. 4 is a vertical sectional view. Fig. 5 is an enlarged fragmentary view of the locking fish-plate, in which is formed the inclined groove. Fig. 6 is an end view of the bolt. Fig. 7 is a 50 side elevation thereof. Fig. 8 is a perspective view of the U-shaped washer.

55 In the drawings the reference-numerals 1 indicate the rails, and 2 indicates the ordinary fish-plate, arranged on one side of the rails, having elongated openings 3 formed therein.

4 represents a locking fish-plate having in-

clined recesses 5 formed therein. In said recesses are slots 6. Said slots are round, as shown at 7, and terminate in the square opening 8.

The reference-numeral 9 indicates notches formed in the base of the fish-plate to receive spikes 10, the latter serving as fastening means and engaging the cross-ties 11.

The reference-numeral 12 indicates the bolt carrying a head 14, said bolt being formed of a round shank portion 15 and a square shank 16, the latter also carrying a head 17.

The reference-numeral 18 indicates a U-shaped washer.

The manner of applying my improved joint is as follows: The ordinary fish-plate 2 is applied to one side of the rails and the bolt applied in proper position, extending through the web of the rail and through the opposite fish-plate, the latter fish-plate 4 engaging the square shank 16 of the bolt, and when the locking fish-plate is moved laterally the shoulders of the head 17 ride up on the inclined face formed adjacent to the openings and produce a wedging action of the fish-plate against the web of the rail, which will securely lock the same in proper position. The locking fish-plate is then spiked to the cross-ties in the usual and well-known manner. The U-shaped washer may be applied when desired to take up any lost motion that may be found in the construction.

The many advantages obtained by the use 85 of my improved rail-joint will be readily apparent from the foregoing description taken in connection with the accompanying drawings, and it will be noted that various changes may be made in the details of construction 90 without departing from the general spirit of my invention.

Having fully described my invention, what I claim as new, and desire to secure by Letters Patent, is—

95 In a rail-joint, the combination of fish-plates having oblong openings formed therein, one of said fish-plates having its outer face provided with recesses the walls of which incline toward the engaging face of the fish-plate, 100 with elongated slots extending through the fish-plate with a rounded opening intermediate to ends of the slot, of bolts, a head on one end thereof, a portion of the shank being

square and a portion round, a head on said square portion, the said square portion of the bolt adapted to engage in the elongated slot and be prevented from turning, the head on 5 said square portion engaging the inclined wall whereby the fish-plate is moved laterally and wedges the bolt, and U-shaped washers adapted to engage between the heads of the bolts

on the other end and the other fish-plate, substantially as described.

In testimony whereof I affix my signature in the presence of two witnesses.

OLIVER S. WEDDELL.
